ELECTRIC SWITCH

Filed Nov. 17, 1927

UNITED STATES PATENT OFFICE.

HARRY A. DOUGLAS, OF BRONSON, MICHIGAN.

ELECTRIC SWITCH.

Application filed November 17, 1927. Serial No. 233,874.

My invention relates to electric switches and resides in improved means for bringing the complementary contacts thereof into and out of engagement and also in an improved 5 construction of component parts of a switch.

The invention has for one of its objects the provision of means whereby a contact carrying bar may be placed in firm engagement with abutments. At least one of said 10 abutments and preferably each of said abutments is a current conducting contact, the bar being preferably metallic to electrically connect said contact abutments when engaging the same. The bar is provided with a 15 spring pressed carrier with which it is in flexible connection, the carrier being adapted to position the bar in a manner to permit the bar to have full engagement with the abutments without being restricted in 20 this function by the carrier. At least one and preferably each of the abutments is in the form of a metallic spring barrel that is suitably connected in circuit and containing a spring which presses upon the carrier 25 to enable the carrier to apply the bar to the spring barrels. The carrier is desirably adapted to turn, there being a fulcrum which is shiftable from side to side to enable the springs to be effective on one side or the other of the fulcrum whereby the springs not only serve to apply the bar to the current conducting spring barrels but also to remove the bar from engagement with the barrels.

I will explain my invention more fully by reference to the accompanying drawing in which Fig. 1 is a sectional view illustrating the preferred embodiment of the invention, the switch shown being closed; Fig. 2 is a 40 sectional view on line 2-2 of Fig. 1; Fig. 3 is a view somewhat similar to Fig. 1 but showing in elevation parts that appear in section in Fig. 1 and also illustrating the switch in open position; Fig. 4 is a sectional view on line 4-4 of Fig. 1; Fig. 5 is a 45 sectional view on line 5-5 of Fig. 1; and Fig. 6 illustrates the carrier and the contact bar operable thereby in separated relation.

The switch structure illustrated includes a cup-shaped metallic casing member 1 whose end wall engages the body portion 2 of a mounting plate 3 and has an annular shoulder 4 which is confined between the 55 body portion 2 of the plate 3 and the flange

5 upon the hollow cylindrical extension 6 of the plate. A disc of insulation 7 closes the cup, this disc being held against the rim of the cup by means of clips 8 which enter recesses in the disc and are clinched 60 over the disc. Two current conducting abutments 9 and 10 are disposed within the casing, these abutments being desirably in the form of metallic spring barrels having reduced extensions 11, 12 which pass 65 through the disc and which are riveted at their outer ends against the outer faces of the disc, as indicated at 13. Binding screws 14 serve to clamp current conducting wires 15 into mechanical and electrical assembly 70 with the spring barrels. Metallic coiled springs 16 are received within the spring barrels as are also the inner ends of the plungers 17 and 18 which are engaged by the springs that press outwardly thereon. 75

A bar 19 is adapted to have engagement with both abutments 9 and 10, this bar having thereon a current conducting contact complementary to each of said abutments. In the preferred embodiment of the invention, said bar is metallic throughout, the portions thereon which are engageable with the abutments being integrally formed therewith. Said bar is flexibly connected with a carrier which is preferably inclusive 80 of a metallic plate 20 and a block of insulation 21 which is clinched upon the plate by the clips 22. Said plate has a rearward extension 23 which is angularly turned at its end where the plate is bifurcated, as indicated at 24. The bar 19 is formed with holes 25 therethrough which receive the bifurcated portions of the plate 20, these portions being brought together after they are passed into said holes, as indicated in Fig. 85 4, whereby the bar is permanently assembled with its carrier. The holes 25 are sufficiently large to enable the bar to swivel or have universal movement upon the carrier to an extent which is sufficient to permit the bar to have firm and extended contact with the contact abutments 9 and 10 whereby the bar is enabled to establish effective 90 low resistance connection between said contacts to close the circuit that contains them. It is obvious that the invention need not be limited to a construction wherein both abutments 9 and 10 are current conducting 95 contacts since the bar 19 may be permanently coupled with one side of the circuit, 100 105 110

as will be readily understood by those skilled in the art.

The block of insulation 21 is formed with flaring recesses 26 which receive the outer, rounded, ends of the spring pressed plungers 17 and 18. A handle 27 carries a fulcrum 28, the handle being shown as being pivoted at 29 between its gripping end and the fulcrum. By turning the handle, the 10 fulcrum 28 is brought into engagement with the insulating block 21 upon one side or the other of the places where the springs 16 have effective pressure upon said block through the intermediation of the plungers 17 and 18. When the handle is in the position shown in Fig. 1, the springs 16 are effective to turn the carrier to bring the contacting bar into engagement with the contacts 9 and 10. When the handle is adjusted to the position shown in Fig. 3, the 20 plungers are upon the other side of the fulcrum to enable the springs to reverse the movement of the carrier and the contacting portion 19 thereon to open the circuit.

25 Changes may be made without departing from the invention.

Having thus described my invention, I claim:

1. In an electric switch, the combination 30 with two abutments of which one is a current conducting contact and one is in the form of a spring barrel; of a spring in said spring barrel; a bar for separable engagement with said abutments and having a contact 35 thereon complementary to the aforesaid contact; and a carrier for said bar and having flexible connection therewith at a place between said abutments, the spring in the barrel being adapted to press upon said carrier in a direction to engage the bar with the abutments when the bar is in circuit closing position.

2. In an electric switch, the combination 45 with two abutments of which one is a current conducting contact and each of which is in the form of a spring barrel; of a spring in each spring barrel; of a bar for separable engagement with said abutments and having a contact thereon complementary to the aforesaid contact; and a carrier for said bar and having flexible connection therewith at a place between said abutments, the springs in the barrels being adapted to press upon said carrier in a direction to engage 50 the bar with the abutments when the bar is in circuit closing position.

3. In an electric switch, the combination 60 with two abutments of which one is a current conducting contact and one is in the form of a spring barrel; of a spring in said spring barrel; a bar for separable engagement with said abutments and having a contact thereon complementary to the aforesaid contact; a carrier for said bar and having 65 flexible connection therewith at a place be-

tween said abutments, the spring in the barrel pressing upon said carrier; a fulcrum for said carrier; and a handle coupled with the fulcrum and serving to shift the fulcrum from either side to the other of the spring 70 to enable such spring to move the bar into and out of engagement with the abutments.

4. In an electric switch, the combination 75 with two abutments of which one is a current conducting contact and each of which is in the form of a spring barrel; of a spring in each spring barrel; a bar for separable engagement with said abutments and having a contact thereon complementary to the aforesaid contact; a carrier for said bar and having flexible connection therewith at a place between said abutments, the springs in the barrels pressing upon said carrier; a fulcrum for said carrier; and a handle coupled with the fulcrum and serving to shift the fulcrum 80 from either side to the other of the springs to enable such springs to move the bar into and out of engagement with the abutments.

5. In an electric switch, the combination 85 with two abutments of which one is a current conducting contact; of a bar for separable engagement with said abutments and having a contact thereon complementary to the aforesaid contact; a spring pressed carrier for said bar and having flexible connection therewith at a place between said abutments; and means for enabling the carrier to be moved in opposite directions by the 90 spring pressure thereon.

6. In an electric switch, the combination 100 with two abutments of which one is a current conducting contact; of a bar for separable engagement with said abutments and having a contact thereon complementary to the aforesaid contact; a spring pressed carrier for said bar and having flexible connection therewith at a place between said abutments; a fulcrum for said carrier; and means for limiting the effective spring pressure 105 upon the carrier to one side or the other of the fulcrum to move the carrier to bring the bar into and out of engagement with said abutments.

7. In an electric switch, the combination 110 with two abutments of which one is a current conducting contact; of a bar for separable engagement with said abutments and having a contact thereon complementary to the aforesaid contact; a spring pressed carrier for said bar and having flexible connection therewith at a place between said abutments; and a fulcrum for said carrier movable to opposite sides of the place where the spring pressure upon the carrier is effective to limit the effective spring pressure upon the carrier 115 to one side or the other of the fulcrum to move the carrier to bring the bar into and out of engagement with said abutments.

8. In an electric switch, the combination 120 with a current conducting contact in the 125

- form of a spring barrel; of a contact complementary to the aforesaid contact; and a spring in said barrel, said complementary contact having a fulcrum shiftable to one side 5 or the other of the line of pressure of the spring whereby the spring presses said complementary contact into and out of engagement with the first mentioned contact according to the position of the fulcrum.
- 10 9. In an electric switch, the combination with a current conducting contact in the form of a spring barrel; of a contact complementary to the aforesaid contact; a spring in said barrel, said complementary contact 15 having a fulcrum shiftable to one side or the other of the line of pressure of the spring whereby the spring presses said complementary contact into and out of engagement with the first mentioned contact according 20 to the position of the fulcrum; and a switch handle operable upon the fulcrum to bring it to one side or the other of the line of pressure of the spring.
10. In an electric switch, the combination 25 with a current conducting contact in the
- form of a spring barrel; of a contact complementary to the aforesaid contact and mounted to turn; a spring in said barrel and serving to press said complementary contact and turn it into engagement with the first contact; 30 and a switch handle operable upon one of said contacts to separate it from the other.
11. In an electric switch, the combination with a current conducting contact in the form of a spring barrel; of a plunger projecting from said spring barrel; a spring within the spring barrel and pressing outwardly upon the plunger; a member upon which said plunger is pressed by the spring; 35 a contact complementary to the spring barrel contact, one of these contacts being mounted to turn and rotatable by the spring through the intermediation of the plunger; and a switch handle operable upon the contact that is mounted to turn and serving to separate it 40 from the other.

In witness whereof, I hereunto subscribe my name.

HARRY A. DOUGLAS.
